UNITED STATES PATENT OFFICE.

ROY N. CUNNINGHAM AND JOHN W. McPHERSON, OF COLUMBUS, OHIO,
ASSIGNORS TO THE AMERICAN CONCRETE MACHINERY COMPANY, OF
COLUMBUS, OHIO, A CORPORATION OF OHIO:

MIXING-MACHINE.

No. 832,722.

Specification of Letters Patent.

Patented Oct. 9, 1906.

Application filed October 20, 1905. Serial No. 283,563.

To all whom it may concern:

Be it known that we, ROY N. CUNNINGHAM and JOHN W. McPHERSON, citizens of the United States, residing at Columbus, in 5 the county of Franklin and State of Ohio, have invented certain new and useful Improvements in Mixing-Machines, of which the following is a specification.

Our invention relates to new and useful 10 improvements in mixing-machines.

The object of the invention is to provide a mixer comprising a drum and a mixing device revolving in opposite directions and mixing vanes or blades carried by the drum 15 coacting with the mixing device, together with a partially hollow shaft having perforations and associated with the mixing device and means for supplying water to the hollow portion of the shaft and causing the same to 20 spray from the perforations.

Another object of the invention is to provide a device of the character described that will be strong, durable, and efficient and simple and comparatively inexpensive to make. 25 and one in which the several parts will not be liable to get out of working order.

With the above and other objects in view the invention consists of the novel details of construction and operation, a preferable embodiment of which is described in the specification and illustrated in the accompanying drawings, wherein—

Figure 1 is a side elevation of our mixer. Fig. 2 is a longitudinal sectional view taken 35 on the line $z-z$ of Fig. 3. Fig. 3 is an elevation of the discharge end of the mixer, and Fig. 4 is a transverse vertical sectional view taken on the line $y-y$ of Fig. 2.

In the drawings the numeral 1 designates a 40 cylindrical drum through which extends a longitudinal shaft 2. The drum is supported on the shaft by spiders 3, which are secured to the inner periphery of the drum and loosely engage about the shaft, so as to turn 45 thereon. At each end the shaft is supported in bearing-boxes 4, which are mounted on standards 5, extending upwardly from a suitable base-frame 6. At its feed end the drum is provided with a head 7, through the 50 central portion of which the annual spout 8 of a feed-hopper 9 projects. By this arrangement the materials to be mixed and which are fed into the hopper 9 are delivered di-

rectly into the drum by the spout 8. Oppositely-disposed blades or vanes 10 are secured 55 to the inner periphery of the drum, so as to project inwardly toward the shaft 2. The blades are set at an angle to the longitudinal axis of the drum. These blades on each side of the shaft are spaced apart and act to force 60 the mixture toward the discharge end of the drum while carrying on the mixing operation. About the shaft 2 and between the blades with respect to their longitudinal disposition collars 11 are secured. From opposite sides of these collars mixing-paddles 12 project, the said paddles on one side of each collar being disposed at an opposite angle to the paddles on the opposite side, both paddles extending at angles to the longitudinal 65 axis of the drum and at different angles from the blades 10, the said paddles, however, being set so as to tend to force the materials toward the discharge end as the mixing operation is carried out. The paddles are of such 70 length as to pass between the blades 10 as the shaft and drum are revolved.

It has been found that the best results are obtained by revolving the drum 1 and its blades 10 in one direction and the shaft 2 and 80 the paddles 12 in the opposite direction. For carrying out this operation we provide on the outer periphery a sprocket-ring 13, which is engaged by a sprocket-chain 14 passing thereabout and running over a small sprocket 85 15, fixed on a drive-shaft 16. The drive-shaft 16 is mounted in a bearing-standard 17 and a bearing-box 18, secured on the side of the standard 5 beneath the hopper 9. The shaft projects beyond the bearing-box 18 and 90 carries a spur-gear 19, which meshes with a gear 20, carried on the end of the shaft 2. Fast and loose pulleys 21 and 22, respectively, are arranged on the shaft 16 in the usual way. Motion being imparted to the 95 fast pulley by suitable means revolves the shaft 16 and the sprocket 15 to the right, reference being had to Figs. 3 and 4. The drum 1 is also revolved to the right by the sprocket-chain 14, the spur-gear 19 being likewise revolved to the right. The spur-gear 19, revolving to the right and meshing with the gear 20, causes the same to revolve to the left, and the gear 20, being fixed on the shaft 2, revolves the same and the paddles 12 to the left. By 100 105 this arrangement the drum and its blades 10

are revolved to the right, while the shaft 2 and its paddles 12 are revolved to the left, so that the materials fed into the drum from the hopper 9 will be thoroughly mixed and gradually forced toward the discharge end of the drum.

The shaft 2 is hollowed out up to a point beyond the center, as indicated at 24, so that perforations 23, extending through the hollow portion, will be disposed centrally of the drum. A suitable packing or plug 25 is inserted in the end of the shaft to close the same, and a pipe 26 is passed through the packing and extends into the hollow portion 15 of the shaft well up into the perforated portion. The horizontal portion 26 of the pipe is connected to a vertically-extending portion 27, in which is arranged a suitable valve 28, so that the amount of water delivered into 20 the pipe 26, and consequently to the hollow portion 24 of the shaft, may be regulated. The portions of the pipe are suitably fixed so as to remain stationary while the shaft revolves about the portion 26. The water or 25 other liquid delivered from the pipe 26 into the hollow portion 24 of the shaft sprays through the perforations 23 from all sides of the shaft, so as to thoroughly dampen the mixture, it being understood that the materials are mixed to the proper degree before 30 being subjected to the spray.

The operation of our mixer is as follows: The materials to be mixed are fed into the hopper 9, from which they will be delivered 35 by the spout 8 into the drum 1. The drum and its blades 10 revolving in one direction and the shaft 2 and the paddles 12 revolving in the opposite direction thoroughly mix the materials and at the same time slightly forcing them forward or toward the discharge 40 end of the drum. When the materials reach the central portion of the drum, they are mixed to the proper degree to receive the water or other liquid which sprays from the 45 perforations 23. The blades 10 and paddles 12 continue to mix the materials and propel the same forward through the moistening or spraying zone to the end of the drum. After passing through the spray the materials 50 which are moistened are thoroughly mixed until they are discharged from the open end of the drum in a perfect mixture, ready for immediate use.

Our machine is more especially designed for mixing concrete, and by regulating the valve 28 either a dry or a wet mixture may be produced. While the machine is more especially adapted for mixing concrete, it is equally as well adapted for use in mixing various materials.

Having now fully described our invention, what we claim, and desire to secure by Letters Patent, is—

1. In a device of the character described, the combination with a rotative open-ended drum, of a plurality of blades secured to the inner surface of said drum and extending toward the axial line thereof, said blades being set at such an angle as to feed material contained in said drum toward the open end 70 thereof, a hopper adapted to feed material to the opposite end of the drum, a shaft which passes through the lower portion of the hopper and through the drum, blades carried by said shaft, means for imparting motion to 75 said shaft in an opposite direction from the rotation of the drum, the blades carried by the shaft being set at such an angle opposite to the angle of the drum-blades as to feed the material contained in the drum toward the 80 open end of the drum, said shaft having an opening formed part way therethrough, and means for conducting liquid to the interior of the hollow shaft.

2. In a device of the character described, the combination with a rotative drum, of blades carried by the inner surface of the drum and projecting toward the axial line thereof, said blades being set at such an angle as to feed material fed to the interior of 90 the drum toward one end thereof, means for feeding material to the opposite end of said drum, a shaft upon which said drum is mounted, a plurality of blades secured to said shaft and extending and working between the blades of the drum, and means for rotating said shaft in the opposite direction from the drum.

In testimony whereof we affix our signatures in presence of two witnesses.

ROY N. CUNNINGHAM.
JOHN W. McPHERSON.
